[57] CLAIM

The ornamental design for a decorative cover for hand stamps, as shown and described.

DESCRIPTION

FIG. 1 is a front perspective view of a decorative cover for hand stamps showing our new design;

FIG. 2 is a front view thereof;

FIG. 3 is a rear view thereof;

FIG. 4 is a right side view thereof, the left side view being a mirror image of the right side view;

FIG. 5 is a top plan view thereof; and,

FIG. 6 is a bottom plan view thereof.

The broken lines depicting the hand stamp body in the figures have been shown for illustrative purposes only and forms no part of the claimed design.

1 Claim, 4 Drawing Sheets
